MACHINE FOR FLAME-HARDENING TRACTOR ROLLER FLANGES

Clady J. Royer, 2645 NW. 26th St., Oklahoma City, Okla.

Filed Mar. 23, 1962, Ser. No. 69,397

Term of patent 14 years

(Cl. D55—1)

FIG. 1

FIG. 2

FIG. 3

FIG. 4

FIG. 5

FIG. 1 is a plan view of the machine for flame-hardening tractor roller flanges showing my new design;

FIG. 2 is a front elevation view thereof;

FIG. 3 is a rear elevation view thereof;

FIG. 4 is a side elevation view thereof; and

FIG. 5 is an elevation view of the opposite side thereof.

I claim:

The ornamental design for a machine for flame-hardening tractor roller flanges, as shown.
